OTHER PUBLICATIONS

"IBEGS's Standard Triangular Sand Nozzles", on sale or public use in the United States prior to at least Apr. 10, 2009.

Primary Examiner — Patricia Palasik*(74) Attorney, Agent, or Firm* — Smith, Gambrell & Russell**(57) CLAIM**

The ornamental design for a nozzle for a sand jet, as shown and described.

DESCRIPTION

FIG. 1 is a side perspective view of the nozzle for a sand jet; FIG. 2 is a bottom perspective view of the nozzle for a sand jet;

FIG. 3 is a first side elevational view of the nozzle for a sand jet, the first side elevational view of the nozzle for a sand jet being a mirror image of a second side elevational view of the nozzle for a sand jet;

FIG. 4 is a rear elevational view of the nozzle for a sand jet;

FIG. 5 is a front elevational view of the nozzle for a sand jet;

FIG. 6 is a top plan view of the nozzle for a sand jet; and,

FIG. 7 is a bottom plan view of the nozzle for a sand jet.
